UNITED STATES PATENT OFFICE

JOHN ROBERT, OF CHICAGO, ILLINOIS, ASSIGNOR TO THE BARRETT COMPANY, A CORPORATION OF NEW JERSEY

WINDING DEVICE

Application filed November 11, 1922. Serial No. 600,269.

This invention relates to a device for winding rolls of paper or the like. It relates more specifically to a device in which a plurality of sheets are wound simultaneously by different operators.

It has been found convenient in certain cases to produce a sheet of greater width than is necessary to be used, in which case the sheet is slit into two or more portions and the individual portions wound on separate rolls. By this invention the separate portions of the slit sheet can be conveniently and rapidly wound on different mandrels or spindles. The invention will be understood from the description in connection with the drawings in which

Fig. 1 represents a side view of the device, Fig. 2 is a plan view of the same, Fig. 3 is a diagram showing the electrical connections, and

Fig. 4 is a detail of one of the elements. In the drawings reference character 1 designates a pulley that is mounted upon a shaft 2 and is driven by belt 3 from any convenient source not shown. The shaft 2 is mounted in bearings 4 and 5 and carries two pulleys 6 and 7 for driving spindles, as will be more fully described below. The shaft 2 also carries loosely mounted thereon a pinion 8 which can be caused to revolve with the shaft 2 by means of the magnetic clutch 9 which may be of the ordinary or usual construction. A chain belt 10 extends from the pinion 8 to a pinion 11 which is rigidly connected to and drives the pull roll 12, which in turn is connected by gearing 13 to another pull roll 14 placed above the roll 12. The roll 15, provided with a slitter 16 is mounted above the roll 17, the rolls 15 and 17 being so mounted that a sheet can be conducted between the two and slit by means of the slitter 16.

Belts 20 and 21 from the pulleys 6 and 7 extend over pulleys 22 and 23 respectively, which are loosely mounted upon the shafts 24 and 25 which carry spindles 26 and 27.

The pulley 22 may be caused to drive the shaft 24 by means of the clutch 28 and the pulley 23 may be made to drive the spindle 27 by means of the clutch 29. The spindles 26 and 27 are provided with longitudinally extending radial slots 30 and 31 for receiving the ends of sheets to be wound.

The shafts 24 and 25 are provided with disks 32 and 33, which have lugs 34 and 35 thereon. A foot lever 40 (see Fig. 4) mounted to turn about the fixed bearing 41 has an arm 42 pivotally connected by a strap 43 to the bar 44, which in turn has levers 45 and 46 connected thereto to turn in fixed bearings 47 and 48. The upper end of the lever 46 is connected to the arm 49, which is mounted on a fixed pivot 50 (Fig. 2) so that the other end of this arm can be projected in the path of the projection 34. The upper end of the lever 45 is connected to the arm 52 which is pivoted at 53 and serves to operate the clutch 28. A similar foot lever 40' is provided for the spindle 27 and the connected parts are the same as already described in connection with the foot lever 40, which it is thought unnecessary to describe again.

Knives 55 are mounted to turn about pivots 56 and are so placed that they may cut off the sheets which rest upon bed plates 57. Rolls 58 and 59, over which the slit portions of the sheet may pass, are revolvably mounted in the positions indicated and tables 60 and 61 are provided for the sheets to pass over the same.

As shown in Fig. 3, the magnetic clutch 9 is connected to any convenient source 62 of electricity. Signal lights 66 and 67 are mounted in view of the operator of the spindle 26, and lights 68 and 69 are mounted in view of the operator of the spindle 27. These lights are connected so as to shine under ordinary conditions. The operator of spindle 26 has access to a push switch or button represented by 70 in Fig. 3 and his foot lever 40 operates the switch 72. In a similar way the operator of spindle 27 can operate switches 71 and

73. These switches 70, 71, 72 and 73 contact with spring pressed insulating blocks 70', 71', 72' and 73' which serve to close the circuits through the lights when these switches 5 70, 71, 72 and 73 are open. The spring pressed insulating blocks serve to open the circuits through the lights 66 and 68 when switch 70 or 71 is closed, and to open the circuit through the lights 67 and 69 when switch 10 72 or 73 is closed. When either operator turns the switch or pushes either button 70 or 71, he thereby breaks the circuit through the lights, but the circuit through the magnetic 9 is not complete until both operators have 15 turned the switches 70 and 71 to the dotted line position. In a similar way the switches 72 and 73 may be operated, but the switches 72 and 73 are connected so as to be operated by the pedals 40 and 40'. In this way as 20 soon as either operator presses his foot on his foot lever, the lights are extinguished but the circuit is not completed through the switches 72 and 73 to operate the clutch 9 until both switches 72 and 73 are turned to the 25 dotted line position shown in Fig. 3.

The operation is as follows:

A sheet of paper or the like is passed under the slitting roll 16 and is slit as indicated, the ends passing between the pull rolls 12 30 and 14, which pull rolls are operated only when the switches 70 and 71 or the switches 72 and 73 are simultaneously closed. The pull rolls are driven, the respective halves of the sheet being carried over the rolls 58 and 59 35 and the tables 60 and 61 until the ends enter the slots 30 and 31 of the spindles 26 and 27. The magnetic clutch 9 can be released and the rolls 14 thereby caused to stop either by one operator opening his switch 70 or by the 40 other operator opening his corresponding switch 71. The operators may cause the pull rolls 12 and 14 to advance the sheet by both closing their respective switches 70 and 71. As soon as the end of either half enters the 45 slot 30 or 31 of the spindles 26 or 27, the corresponding operator can stop the pull rolls by releasing his switch and may then start his spindle to turning by pressing his foot upon the foot lever 40 or 40', thus operating 50 the corresponding clutch 28 or 29 to drive the spindle 26 or 27. The clutches 28 and 29 are friction clutches and are such that they will slip unless the sheet is being advanced by the pull rolls 12 and 14. It will be seen 55 from the description that both operators have control of the pull rolls and that neither one can start the pull rolls 12 and 14 until the other one is ready to begin winding his portion of the sheet. Also, each receives a signal, when the other one is ready, by the lights 60 being extinguished. When the proper number of convolutions have been wound on the spindles 26 and 27 the winding can be stopped by either operator removing his foot from 65 his foot lever, whereupon both operators cut

off the sheets with the knives 55 and remove the rolls, and prepare the spindles for the reception of the other ends of the sheets. When the foot levers are in their normal position, the lugs 34 and 35 of the disks 32 and 70 33 will contact with the end of the arms 50, thus stopping the spindles so that the slots 30 and 31 are in the proper positions to receive the ends of the sheets. If one operator is more prompt than the other one in getting 75 ready to start, he will not be able to start up the pull rolls 12 and 14 until the other one is also ready to wind up his half of the sheet.

I claim:—

1. In a device of the class described, means 80 for advancing portions of a slit sheet and winding the portions separately, and a controller for each of said winding means, said controllers being in series for controlling said advancing means.

2. In a device of the class described, pull 85 rolls, a clutch for controlling said pull rolls, a winding device for each portion of a slit sheet, a clutch for each winding device, means associated with each of said last named 90 clutches and dependent upon the actuation thereof for controlling said pull roll clutch.

3. In a device of the class described, pull 95 rolls, a magnetic clutch for controlling said pull rolls, an electric circuit for said clutch, a plurality of winding devices, a clutch for each winding device, and contacts associated with the operating means of said last named 100 clutches whereby said electric circuit is closed only when all of said last named clutches are actuated.

4. In a slitting machine, pull rolls, a plurality of winding rolls, and means whereby the actuation of said pull rolls is dependent upon the actuation of all of said winding 105 rolls and whereby the stopping of said pull rolls will occur upon the stopping of any one of said winding rolls.

5. A winding device comprising pull rolls, a winding shaft, a winding roll rigidly 110 mounted upon said shaft, driving means for said shaft and means for operably connecting said driving means to said shaft and for locking said winding roll and stopping the pull rolls upon the release of said connecting 115 means.

6. In a slitting machine, pull rolls, a plurality of winding rolls and means whereby the stopping of said pull rolls is dependent upon the stopping of only one of said winding 120 rolls.

7. In a winding device pull rolls, a plurality of winding rolls, means for driving said rolls and control elements associated with said winding rolls, said elements being 125 independently movable to cause the pull rolls to be disconnected from the driving means therefor.

8: In a device of the class described, pull 130 rolls, a plurality of winding rolls, means for

driving all of said rolls; and independently operable control elements movable to render the driving means for a winding roll and the pull rolls inoperative, the starting of the 5 pull rolls being dependent upon the actuation of the driving means for all the winding rolls.

9. In a winding device, pull rolls, a plurality of winding rolls, means for driving said rolls including a drive means for each of 10 the winding rolls, and elements controlling the operation of the driving means for the pull rolls, the said elements being operated by the joint actuation of the driving means for all of the winding rolls.

15 In testimony whereof I affix my signature.
JOHN ROBERT.
